UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

FILING APPLIANCE.

1,242,694.

Specification of Letters Patent.

Patented Oct. 9, 1917.

Application filed August 4, 1914. Serial No. 854,975.

To all whom it may concern:

Be it known that I, HARRY J. HICK, a citizen of the United States, residing at Alliance, in the county of Stark and State 5 of Ohio, have invented certain new and useful Improvements in Filing Appliances, of which the following is a specification.

The invention relates to a filing appliance for sales bills and other similar papers, 10 in which a plurality of bill holders are operatively mounted in a case or cabinet in which they are adapted to be singly or collectively rotated from upright to reclined position for giving access to both sides of each holder.

15 The improvement relates more particularly to that class of filing appliances in which a series of bill holders are normally placed in upright position and have their lower ends hinged together; and in which 20 the foremost holder is supported on a pivotal bearing, while the rearmost holder is supported and guided by suitable means for holding it in upright position during the operation of the other holders, and all 25 the holders are normally held in upright position by the action of gravity.

The object of the present invention is to provide improved means for supporting and guiding the rearmost holder of the series so 30 that it will be maintained in upright position at all times during the operation of the forward holders of the series. This object is attained by providing a movable carriage with upright guideways therein for 35 controlling the movements of the rearmost holder during the operation of the other holders, and with horizontal guideways therein having sliding engagement with the hinged end of the foremost holder.

40 A preferred embodiment of the invention, thus set forth in general terms, is illustrated in the accompanying drawings, forming part hereof, in which—

Figure 1 is a side elevation section of a 45 filing case showing a series of bill holders located in upright position therein;

Fig. 2, a side elevation of the same partly in section showing all the bill holders excepting the rearmost one rotated forward 50 into reclined position;

Fig. 3, a detached perspective view of the bearing plate 7; and

Fig. 4, a detached perspective view of the controlling carriage.

Similar numerals refer to similar parts throughout the drawings.

The case may be composed of the substantially rectangular bottom or base section 1 and the top or cover section 2, which may be operatively connected together by 60 means of the guiding hinge brackets 3, one bracket being located on each side of the rear end portion of the base section, by means of which the cover section can be swung and shifted upon the base section to 65 aline either the top or rear end of the cover section with the rear end of the base section, as more fully set forth in my co-pending application filed July 27, 1914, Serial No. 853,254.

70 The series of bill holders 4 and 4' are hinged together at the lower rear ends, and the pivot 5 between two adjoining intermediate holders 4^a and 4^b' may be mounted in bearings 6 formed or secured on the protruding edge of the bearing plate 7, which is secured to the rear end of the cover section of the case; so that the holders above this bearing may be referred to as the upper 75 division of the series, and the holders below this bearing may be referred to as the lower 80 division of the series.

The lower forward holder 4^a' of the series may be pivoted at 8 to the rear end of the frame 9, which may carry an index, not 85 shown, for the bill holders; and this frame may normally rest upon the jointed tracks 10 having their forward ends pivoted in the forward end of the base section and their rear ends resting and sliding on the bottom 90 thereof; which tracks may serve to support and guide the forward end of the frame upward and over the forward rim of the base section during the opening and closing 95 operation of the cover section of the case.

The jointed tracks 10 may also be provided with suitable spring means, as 11, for thrusting the tracks upward to elevate and sustain the rear end of the frame 9 for the proper operation of the lower division of 100 bill holders 4', 4^a' and 4^b'; but these devices, which are made the subject-matter of my co-pending application filed July 23, 1914, Serial No. 853,600, do not form any part of the invention claimed herein, which is concerned more particularly with the operation 105 of the upper division of the series of bill holders 4, 4^a and 4^b.

The bearing plate 7 is secured to the rear end wall 12 of the cover section of the case and is carried into horizontal position when the cover section is rotated into upright position, as shown in Figs. 1 and 2, and in this position these parts may be referred to as a support for the upper division of holders. The bearing plate 7 may also have the upward and inward turned L-flanges 13 on its side edges to form guides for the controlling carriage.

The controlling carriage is composed of the upright back plate 14 having forwardly turned flanges 15 on the side edges, which, in turn, are provided with the inwardly turned flanges 16 in their lower portions forming the channel guideways 17 adapted to engage the side edges of the rearmost holder 4^b for guiding it upward and downward as one or more of the foremost holders of the upper division are operated from upright to reclined position, and vice versa.

The back plate 14 is also provided with the brackets 18, one being formed or secured on each lower corner thereof; and each of these brackets is preferably provided with a wheel or roller 19 adapted to ride forward and rearward upon the rear end 12 of the cover section of the case when the same is in horizontal position to serve as a support for the carriage. The lower corners of the back plate and the flanged portions thereof are cut away or notched as at 20 to receive the flange guides 13 formed on the side edges of the bearing plate 7, by means of which the controlling carriage is directed and held truly in transverse position during its forward and rearward movements.

The brackets 18 are provided with the forwardly projecting plates 21 provided with the longitudinal slots 22 adapted to receive and operate on the guiding pivot pins 23 projecting laterally from the lower end portion of the foremost bill holder 4^a of the upper division adjacent to the hinged end thereof; which pivot pins by their engagement in the horizontal ways formed by the slotted bracket plates, serve to hold the back plate 14 in upright position during its forward and rearward movement in the operation of the holders. The location of the pivot pins 23, with reference to the pivot 5 in the bearing 6, may be such that when the foremost frame 4^a of the division is rotated into reclined position, the pivot 23 will be slightly elevated, thereby tilting the back plate 14 slightly rearward as the controlling carriage moves forward with the rearmost

holder 4^b, as shown in Fig. 2. In the operation of one or more of the upper division of bill holders it is evident that when the rearmost holder is carried forward and rearward by the rotation of the foremost holders, it also moves upward and downward; during which upward and downward movement it slides and is held in upright position by the guideways 17 on the sides of the back plate 14; and during which forward and rearward movements the controlling carriage travels forward and rearward by riding on the wheels 19 and sliding upon the pins 23 operating in the slots 22, which serves to maintain the guideways 17 in upright position at all times.

I claim:

1. A filing appliance including a plurality of normally upright holders having their lower ends hinged together, a pivotal support for the hinged end of one end holder, and a controlling carriage in operative engagement with the pivoted end holder and in guiding engagement with the other end holder.

2. A filing appliance including a plurality of normally upright holders having their lower ends hinged together, a pivotal support for the hinged end of one end holder, and a controlling carriage for the other end holder movable to and from the pivotal support and having upright ways in which said last named holder is movable upward and downward and horizontal ways in sliding engagement with a relatively fixed pivot pin adjacent the hinged end of the pivoted holder.

3. A filing appliance including a plurality of normally upright holders having their lower ends hinged together, a pivotal support for the hinged end of one end holder, and a controlling carriage in operative engagement with the pivoted end holder and having upright guide-ways for the other end holder.

4. A filing appliance including a plurality of normally upright holders having their lower ends hinged together, a pivotal support for the hinged end of the foremost holder, and a controlling carriage having sliding engagement with the foremost holder and guiding engagement with the rearmost holder.

HARRY J. HICK.
